UNITED STATES PATENT OFFICE.

JOSEPH SAUER, OF MILLVALE, PENNSYLVANIA.

WRENCH.

SPECIFICATION forming part of Letters Patent No. 761,411, dated May 31, 1904.

Application filed November 20, 1903. Serial No. 181,950. (No model.)

To all whom it may concern:

Be it known that I, JOSEPH SAUER, a citizen of the United States of America, residing at Millvale, in the county of Allegheny and State of Pennsylvania, have invented certain new and useful Improvements in Wrenches, of which the following is a specification, reference being had therein to the accompanying drawings.

This invention relates to certain new and useful improvements in wrenches, the primary object of the invention being to provide novel means for the rapid adjustment of the movable jaw and the secure holding of the said jaw in its adjusted position.

Briefly described, the invention comprises a wrench-shank provided on its outer end with a rigid jaw and which wrench-shank is slotted throughout the major portion of its length, forming a spring-bar which lies parallel with the wrench-shank and has teeth on one face. The free end of this bar extends into the recess provided therefor in the rigid jaw of the wrench and is at all times under the tension of the spring arranged in said recess. The movable jaw is mounted on the wrench-shank and has means for engagement with teeth on the wrench-shank proper and also with teeth on the spring-bar. A pivoted dog is provided, which carries a cam adapted to be inserted in the slot in the spring-bar and wrench-shank proper for forcing the spring-bar outwardly, and thereby securely locking the movable jaw in its adjusted position.

All of the above construction, together with such other details as enter into my invention, will be hereinafter more fully described, and specifically pointed out in the claims.

In describing the invention in detail reference is had to the accompanying drawings, forming a part of this application, and wherein like numerals of reference indicate like parts throughout the several views, in which—

Figure 1 is a plan view of a wrench constructed in accordance with my invention, the rigid jaw being partly broken away. Fig. 2 is a longitudinal sectional view of the wrench. Fig. 3 is a detached detail perspective view of the locking-lever. Fig. 4 is a longitudinal sectional view of a part of the wrench.

Fig. 5 is a transverse vertical sectional view through the wrench-shank.

In the accompanying drawings, 1 indicates the wrench-shank, to the one end of which is secured in any desirable manner a suitable handle 2 and on the outer end of which shank a rigid jaw 3 is carried. This wrench-shank is provided with a longitudinal slot 4, extending from the outer end of the shank to a point near its inner end, forming a spring-bar 5, the outer end of which bar extends into the recess 6, provided therefor in the inner face of the rigid jaw 3, and in which recess between the spring-bar and the end of the recess is arranged a spring 7, the tension of which is always against the bar 5. This bar 5 is provided with teeth 8 on its rear face, while the wrench-shank is provided on its outer face with teeth 9. Lugs or stops 10 11 are provided on the wrench-shank and spring-bar, respectively, near the inner end thereof, to limit the inward movement of the movable jaw. The movable jaw 12 is mounted on the wrench-shank and spring-bar and has projecting into the opening which receives the wrench-shank and bar the teeth 14 15, which engage with the teeth 9 on the wrench-shank, and on the outside wall of said opening is provided with teeth 16 17, which engage with teeth 8 of the spring-bar. Means is provided for locking the movable jaw in its adjusted position, and to this end I provide the said movable jaw on its one face with a boss 18, bifurcated to form a pair of lugs 19, in which is pivoted a locking-lever 20 by means of the pivot-pin 21, engaging the lugs 19 and the eye 22, carried by said lever. This lever also carries a cam or wedge 23, which is adapted to enter the slot 4, whereby to force the bar 5 outwardly. When the lever 20 is raised so as to move the cam or wedge 23 out of the slot 4, as seen in dotted lines in Fig. 2, the movable jaw 12 is free to be forced in either direction on the wrench-shank, and when the jaw has been moved to its desired position the lever 20 is closed toward the shank, thus inserting cam or wedge 23 in the slot and firmly holding the jaw 12 in its adjusted position.

In the practice of the invention it will be evident that various slight changes may be

made in the details of construction without departing from the general spirit of my invention.

Having fully described my invention, what I claim as new, and desire to secure by Letters Patent, is—

1. In a wrench of the type described, a wrench-shank having a handle at its inner end and a rigid jaw at its outer end, said rigid jaw provided on its inner face with a recess, a spring-bar carried by the wrench and having its outer end extending into said recess in the jaw, a movable jaw mounted on the wrench-shank and spring-bar, and a locking-lever carried by the movable jaw and having a cam adapted to be inserted between the shank and the spring-bar for locking the movable jaw, substantially as described.
2. In a wrench, a wrench-shank provided at its outer end with a rigid jaw having a recess, a spring-bar carried by the shank with its free end extending into said recess, a spring in said recess bearing against said spring-bar, a movable jaw mounted on the shank and on said spring-bar, a locking-lever pivoted to said jaw, and a cam or wedge carried by said locking-lever to be engaged between the shank and the spring-bar, as and for the purpose described.
3. In a wrench, a wrench-shank provided

with teeth, a jaw carried by the outer end of said wrench-shank and having a recess, a spring-bar carried by the shank, said spring-bar provided with teeth and having its outer end extending into the recess in said jaw, a movable jaw mounted on the shank and spring-bar, and having teeth for engagement with the teeth on said shank and spring-bar, and means for engagement between the shank and spring-bar for locking the movable jaw in an adjusted position, substantially as described. 45

4. In a wrench, a shank divided longitudinally, in combination with fixed and movable jaws, said shank passing through the movable jaw, and a cam passing between the divided portions of said shank.

5. In a wrench, a shank formed with a longitudinal slot extending through one of its ends, a jaw slidable thereon, and an expanding means carried by said jaw and passing through said slot, substantially as and for the purpose specified. 50

In testimony whereof I affix my signature in the presence of two witnesses.

JOSEPH SAUER.
